L. BUCKNER

TWO-PART HEEL

Filed Sept. 17. 1921

INVENTOR
Leon Beckner
BY
Pennie Davis, Merlin & Edwards,
his ATTORNEYS

UNITED STATES PATENT OFFICE.

LEON BUCKNER, OF NEW YORK, N. Y.

TWO-PART HEEL.

Application filed September 17, 1921. Serial No. 501,415.

To all whom it may concern:

Be it known that I, LEON BUCKNER, a citizen of the United States, residing at New York city, in the county of New York, State 5 of New York, have invented certain new and useful Improvements in Two-Part Heels; and I do hereby declare the following to be a full, clear, and exact description of the invention, such as will enable others skilled 10 in the art to which it appertains to make and use the same.

This invention relates to detachable heels which are preferably made of some such resilient material as rubber, although any desired material might be used.

In my copending application, Serial No. 491,922, filed August 13, 1921, there is shown a number of different forms of two-part detachable heels. This invention also 20 relates to two-part detachable heels, the inner part being preferably attached more or less permanently to the shoe and the outer part, which is preferably U-shaped, being made readily detachable and being provided 25 with various means, as will be described for holding the outer heel in place.

The inner heel is preferably made of a solid block of rubber or equivalent resilient material and as has been stated, is nailed to 30 the shoe. The outer heel is substantially U-shaped and extends around on the outside of the inner heel, the two together cooperating to form a complete heel. This invention is more particularly concerned with various 35 mechanisms for attaching the outer heel to the inner heel so that the outer heel may be readily taken off by the user, after it has become worn, and a new one readily put in place, without the necessity of going to a 40 shoemaker, as is usually the case.

In accordance with this invention the outer heel slidably engages the inner heel and is slid into engagement with the inner heel.

45 The advantage of having a two-part heel comprising an inner and an outer portion is that inasmuch as most of the wear on a heel when in actual use takes place on the outer part, a practically new heel may be had, according to this invention, by simply taking off the worn outer part and putting a new outer part in place. Furthermore, according to this invention, this may be 50 done by the user of the heel himself, without the necessity of going to a shoemaker.

In the accompanying drawings—
Fig. 1 is a plan view of the ground side of the two-part heel;

Fig. 2 is a section on the line 2—2 of Fig. 1.

To describe the drawings more in detail, 60 30 indicates the inner heel, which may be a solid block of rubber attached to the shoe 2 by the fastening elements 3. The periphery of this inner heel is substantially U-shaped. The inner heel, at its front and rear ends, on the side adjacent the shoe, is undercut, as indicated at 37.

Referring first to Fig. 1, the inner heel 30 carries a plate 32 provided with saw cuts 70 33 defining an elastic tongue 34. Two latching lugs 35 are struck from the tongue portion. Two other latching lugs 36 are struck from the rear part of the plate 32. The inner heel is undercut at the front and 75 rear, adjacent the shoe, as indicated at 37. The lugs 35 and 36 extend into the undercut portions.

The outer heel 6 has embedded in it a plate 38, which is more or less U-shaped, the 80 inner edges of this plate being indicated at 39. A central tongue 40 carried by the plate defines two notches 42 for the lugs 36. At the front the outer plate has two apertures 43 cut in which the lugs 35 engage. The 85 outer heel is put in place by sliding from the left, the outer plate 38 engaging over the inner plate 32, the lugs 36 seating in the notches 42 and the lugs 35 engaging in the apertures 43. In order to remove the outer 90 heel, the tongue 34 is moved away from the shoe, thus disengaging the lugs 35, whereupon the heel is removed by sliding it to the left.

While the invention has been illustrated 95 in one form, it should be understood that mechanical details may be considerably modified within the principle of the invention and that therefore the invention is not limited to any precise structural embodiment. It should also be understood while rubber is the preferred material, either or both parts of the heel may be made of any desired material.

I claim as my invention:

1. A two part heel comprising an inner heel portion attached to the shoe, a U-shaped outer heel portion of resilient material, plates carried respectively by the inner and outer heel portions, and latching means car- 100 110

ried by said plates for latching them together for holding the two heel portions in place.

2. A two part heel comprising an inner heel portion attached to the shoe, a U-shaped outer heel, plates respectively carried by the inner and outer heel and adapted to slidably engage each other, and latching means associated with said plates for latching them together.

3. A two part heel comprising an inner heel portion attached to the shoe, a U-shaped outer heel, plates respectively carried by the inner and outer heel and adapted to slidably engage each other, latching means associated with said plates for latching them together, and a finger piece carried by one of the plates for unlatching purposes.

4. A two part heel comprising an inner heel portion attached to the shoe, a plate provided with latching lugs, carried by the inner heel, a U-shaped outer heel and a plate embedded in the outer heel provided with latching openings adapted to be engaged by the said latching lugs when the outer heel is slidably engaged with the inner heel.

5. A two part heel comprising an inner

heel portion attached to the shoe, a plate carried by the inner heel, an elastic tongue formed as part of the said plate, a latching device carried by said tongue, a U-shaped outer heel, and a plate carried by the outer heel, provided with means for cooperating with the said latching device for latching the two said plates together.

6. A two part heel comprising an inner heel portion attached to the shoe, a plate carried by the inner heel, an elastic latching element carried by said plate, a U-shaped outer heel, and a plate carried by the outer heel for slidably engaging with the plate carried by the inner heel, provided with latching means for cooperating with the latching element on the inner heel plate.

7. A two part heel comprising an inner heel portion attached to the shoe, a plate carried by the inner heel portion, a U-shaped outer heel portion, a plate carried by the outer heel portion, said two plates adapted to slidably engage each other, latching means associated with the two plates, and manually operated means for actuating the latching means.

In testimony whereof I affix my signature.
LEON BUCKNER.
